UNITED STATES PATENT OFFICE.

WILLIAM HIBBS, OF PLANO, ILLINOIS, ASSIGNOR TO INDEPENDENT HARVESTER COMPANY,
OF PLANO, ILLINOIS, A CORPORATION OF MAINE.

CORN-HUSKING MACHINE.

No. 902,729.

Specification of Letters Patent.

Patented Nov. 3, 1908.

Original application filed January 26, 1907, Serial No. 354,013. Divided and this application filed August 7, 1907.
Serial No. 387,407.

To all whom it may concern:

Be it known that I, WILLIAM HIBBS, a citizen of the United States, residing at Plano, in the county of Kendall and State of Illinois, have invented new and useful Improvements in Corn-Husking Machines, of which the following is a specification, reference being had to the accompanying drawings, forming a part thereof.

10 This application is a division of my application Serial No. 354,013, filed Jan. 25, 1907. It relates to certain portions of the husking mechanism of the corn-gathering machine, and it consists of the features of construction 15 shown and described as indicated in the claims.

In the drawings:—Figure 1 is a partly sectional side elevation of a portion of a corn-gathering machine containing the features 20 constituting my invention, section being made in fore-and-aft plane across the lower end of the ear-delivering conveyer which is not otherwise shown. Fig. 2 is a view looking in the direction of the arrows at the line 25 2—2 on Fig. 1. Fig. 3 is a section at the line 3—3 on Fig. 1.

The type of machine to which this invention relates may be understood as being a two-wheeled machine, the position of one of the 30 wheels being indicated in dotted line at 1 in Fig. 1, the wheels not being otherwise shown, the stalks being engaged between gathering arms not shown and directed to snapping rolls, 3, 3, between which they are engaged for snapping off the ears, which are thereupon carried up rearward along the snapping rolls by mechanism not shown and delivered from the upper rear end thereof into a downwardly and rearwardly inclined chute or guideway, 40 19, the bottom of which is formed by husking rolls. The features of the present invention relate to the husking rolls and devices associated with them. These husking rolls, as illustrated, consist of two pairs of rolls, 4, 4, 45 4, 4. Each of said rolls is provided with longitudinal rows of pockets or recesses, 4^a, and intermediate them, rows of pins or studs, 5, which are preferably provided with expanded or dove-tailed heads and are adapted to 50 enter the pockets of the adjacent rolls. These pins or studs may be formed of ordinary wood screws set in rows, having customary counter-sinking heads which are of suitable diameter to enter the pockets, 4^a, and engage

with the husks so as to secure their subsequent engagement between the two rolls, and so to effect with greater certainty their detachment from the ears. In addition to the grooves and pins for engaging them, one of the rolls of each pair may be provided with 55 ribs, 6, 6, and the opposite roll of the pair with corresponding grooves, 7, 7, to receive the ribs and thereby grip the husks more securely than they would be gripped by the smooth surfaces of the rolls, or each of the 60 rolls of the pair may be provided with a rib, 6, and a groove, 7, the rib and groove of one being adapted to engage the groove and rib of the other.

Another feature of the husking mechanism 70 constituting part of this invention consists in retarding devices overhanging the husking rolls to prevent the ears from sliding down along the rolls so rapidly as to prevent engagement with the husks. These retarding 75 devices consist of weighted wings or flaps, 10, which are hung upon rock shafts, 11, extending across the husking trough or chute, 19, of which the rolls form the bottom, in such 80 position that the wings or flaps rest by gravity upon or against the husking rolls when the trough is empty, and are adapted to be swung or crowded off the rolls by the ears sliding down the latter, as seen in Fig. 1. In order to adjust these retarding devices to 85 prevent them from too greatly retarding the descent of the ears and so causing an accumulation, the rock shafts, 11, are provided with stop collars, 12, whose projecting fingers, 12^a, engage under the weighted flaps, 10, and lift 90 the flaps or swing them rearward off the rolls when the shafts are rocked for that purpose. All the rock shafts are also provided with lever arms, 13, outside the trough, 19, and these lever arms are connected by a link bar, 95 14, which being moved longitudinally rocks all the shafts, engaging the projecting fingers, 12^a, of the collars, 12, with the flaps or wings, 10, and lifting them all equally away from the husking rolls to any degree found necessary in order to prevent undue retardment 100 of the ears. When the husks are very heavy or green and tend to slide less easily or require more room than when they are scanty or very dry, the flaps, 10, will be adjusted to 105 allow a little more room for the ears. For this purpose, the link bar, 14, has a plurality of notches, 14^a, any one of which may be en-

gaged by the detent tooth, 15^a, of the bracket, 15, which is secured on the side of the trough, 19, such engagement holding the bar at any position to which it may be adjusted to adjust the retarding wings or flaps, 10.

I claim:—

1. In a corn husking machine, in combination with a descending chute for the detached ears and husking devices operating in said chute; weighted flaps or wings pivoted over the chute for depending in the path of the descending ears to retard their descent, and means for stopping said flaps short of the bottom of the chute, and means for adjusting said stopping devices to limit and vary the intrusion of the flaps into the path of the ears along the chute.

2. In a corn husking machine, in combination with a descending chute for the detached ears; husking devices operating in the bottom of the chute; rock shafts extending across the chute and weighted flaps or wings pivoted thereon and depending therefrom into the chute into the path of the descending ears to retard their descent; coöperating stops on the rock shaft and the wings pivoted thereon, for limiting the swinging movement of the flaps about the shafts toward the path

of the ears, and means for adjusting the shafts by rocking to limit the protrusion of 30 the flaps into the path of the ears.

3. In a corn husking machine, in combination with a descending chute for the detached ears; husking devices operating at the bottom of said chute; rock shafts extending 35 across the chute; weighted flaps pivoted on the rock shafts and depending into the chute in the path of the ears; coöperating stops on the rock shafts and the depending flaps or wings for limiting the swing of the flaps about 40 the rock shafts toward the path of the ears; lever arms on the rock shaft outside the chute; a link bar connecting said lever arms for rocking all the shafts equally to adjust the stops and limit the protrusion of the 45 wings into the path of the ears, and means for releasably securing said link bar at adjusted position.

In testimony whereof, I have hereunto set my hand at Plano, Illinois, this 3 day of 50 August, 1907.

WILLIAM HIBBS.
